W. GRIESBACH

LABEL HOLDER

Filed March 22, 1923

22 INVENTOR.
William Griesbach

BY
Harry W. Brown,
ATTORNEY

UNITED STATES PATENT OFFICE.

WILLIAM GRIESBACH, OF GREENFIELD, MASSACHUSETTS.

LABEL HOLDER.

Application filed March 22, 1923. Serial No. 626,780.

To all whom it may concern:

Be it known that I, WILLIAM GRIESBACH, a citizen of the United States of America, residing at Greenfield, county of Franklin, 5 Commonwealth of Massachusetts, have invented certain new and useful Improvements in Label Holders, of which the following is a specification.

This invention relates to improvements in 10 devices for holding and retaining a label in place for the purpose of indicating the name of an article and the price of the same in a receptacle or container.

An object of the invention is to provide 15 a device for holding a label which may be readily attached to and detached from a suitable container as boxes having a glass front in which are placed different kinds of articles for sale, as biscuits, cookies or confectionery.

Heretofore, it has been a common practice to attach a label directly to the glass door of a receptacle by pasting or glueing for indicating its contents and the price.

25 This has been found objectionable as the label oftentimes loosens or becomes fully detached from the glass, leaving the container without any means of indicating its contents or the price, and also leaving the 30 surface of the glass smeared or covered with paste or glue, which is unsightly and detracts from the salability of the article.

The present invention, is therefore, designed to overcome these objections and to 35 provide a label holding device that is neat in appearance, one that can be readily attached to and removed from the receptacle, one that will maintain the label clean and free from contact with the hand of the user 40 of the receptacle and one that can be readily changed and another substituted, if necessary.

Broadly, my improvement comprises a 45 member having oppositely located folded edges for receiving the oppositely located edges of the label and means connected to the label receiving member for retaining the member in place and attached to the receptacle, said means comprising in general 50 sharpened or pointed ends which will embed themselves in the wooden part of the casing, and a spring actuated bar for exerting sufficient pressure at the ends of the label receiving member to retain the member in 55 place and yet permit the label receiving

member to be readily removed from the receptacle or container.

Referring to the drawings:

Fig. 1 is a partial sectional view on the line 1—1 of Fig. 2 showing the device in 60 place and the manner of attaching it to the inside of the container's door.

Fig. 2 is a front elevational view partially in perspective showing the hinged door of the container which door is supplied with 65 the usual glass front.

Fig. 3 is an enlarged detail view of the device detached from the container and illustrating one of the indicating labels with a name shown thereon to indicate the 70 contents and the price.

Fig. 4 is a detail view of one of the labels removed from the device.

Fig. 5 is an enlarged side elevational view of the complete device similar to the view 75 shown in Fig. 1 but removed from the container, and

Fig. 6 is a perspective view on the line 6—6 of Fig. 3, illustrating the folded edges 80 of the label receiving member for retaining the label in place.

Referring to the drawings in detail:

The opposite sides of the door of the container are indicated at 1 and 2 and 3 indicates the door as a whole which is hinged 85 at its bottom edge to the container indicated at 4. This door is provided with a glass front 5 through which the articles being offered for sale may be readily observed. The articles are conventionally indicated by 90 the dotted line 6. Extending along the inner surfaces of the opposite sides 1 and 2 of the door are strips of wood 7 and 8. 9 designates as a whole the member which receives the label. This member as shown is 95 formed with the oppositely located folded edges 10 and 11 to form a channel into which the label indicated at 12 may be slipped or inserted. The left hand end of the member 9 is offset or bent inward, indicated at 13 100 and its end is formed with sharpened teeth or projections 14 for engaging the strip of wood 7. Located at the right hand end of the member 9 is a spring actuated and slideable bar 15 which slides through the upwardly extending portions 16 and 17. The bar 15 is formed with an end or finger part 18 for operating the same. The opposite or outer end of the bar 15 is provided with an enlarged head portion 19 which is also 110

formed with sharpened teeth 20 for engaging the strip of wood 8. A spring 21 is loosely located upon the bar 15 and extends between the upwardly extending part 17 and 5 the head 19, as shown in Fig. 3.

The device is applied or attached to the inside of the door 3 by the operator grasping the upwardly extending finger part 18 and placing the spring 21 under compression. This permits the distance between the 10 extreme ends of the member to be shortened so that it may be inserted between the wooden strips 7 and 8. When the operator releases his hold on the part 18 the spring 15 21 will force the sharpened teeth 14 and 20 into the wooden strips 7 and 8 a sufficient depth to retain the member 9 in place.

It is to be understood that the label or 20 card bearing the name of the article contained in the receptacle and the price of the same is first inserted or slipped into the part 9 as shown in Fig. 6. This device therefore permits the label to be readily attached to the container and at the same time permanently 25 retained by it in place so that it cannot become detached, or soiled, when the door 5 is opened.

From this description it will be seen that the label holding device may be readily attached to and removed from the door and a new label substituted when desired, or necessary, and one that will not become detached or disarranged when in use.

The purchaser can readily determine the 30 contents of the box as well as the price of the articles contained therein. The parts 16 and 17 may be formed as a struck up portion of the part 9 or they may be attached to a separate bar or base 22 and 35 secured to the part 9 by soldering.

What I claim is:

1. A device for the purpose described comprising a member formed with turned over edges to provide a channel for receiving a label, said member having its opposite 40 ends provided with sharpened serrations or teeth-like structures which will serve to retain the device in place, means comprising a spring actuated bar located at one end of

the device for exerting pressure on the opposite ends of the device for causing the teeth to engage the inner sides of a container for retaining the same in place. 50

2. A device for the purpose described, comprising a member having a channel like 55 portion into which a label or the like may be slipped, said member having one end formed with serrations or sharpened points, the other end of the member having a slide- 60 able bar attached thereto, a spring on the bar for forcing the same against the inner sides of the container, whereby the device as a whole may be retained in place by the action of the spring.

3. A label device for the purpose de- 65 scribed comprising a channel like member designed to detachably receive a label on which is displayed the contents of the receptacle and the price of the articles contained therein, and which may be slipped 70 into the end of said member, one end of the member having serrations, a slideable bar attached to the member, said bar having a portion at one end for operating the same and a sharpened or teeth like portion at its 75 opposite end, a spring for forcing the sharpened portions of the device against the inner sides of the container whereby the device as a whole is retained in place and may be removed by withdrawing the spring 80 actuated bar as described for removing and inserting a new label.

4. A label receiving device comprising a member having a U-shaped channel for receiving and retaining the label, a spring 85 actuated device attached to said member in parallel relation thereto for retaining the member in place by engaging the inner sides of a door of a container.

5. A label receiving device comprising a 90 channel shaped member for detachably receiving a label, the opposite ends of the device having serrations for engaging the inner opposite sides of the door on which the device is designed to be placed, and 95 spring actuated means for forcing the serrations against the said sides as described.

WILLIAM GRIESBACH.
